UNITED STATES PATENT OFFICE.

GUSTAV A. BARTH, OF ST. LOUIS, MISSOURI, ASSIGNOR TO PIERRE CHOU-
TEAU, OF SAME PLACE.

STEAM OR PNEUMATIC ENGINE.

SPECIFICATION forming part of Letters Patent No. 393,604, dated November 27, 1888.

Application filed April 17, 1888. Serial No. 270,928. (No model.)

To all whom it may concern:

Be it known that I, GUSTAV A. BARTH, a citizen of the United States, residing at the city of St. Louis, State of Missouri, have invented certain new and useful Improvements in Direct-Acting Steam or Pneumatic Engines, of which the following is a full, clear, and exact description.

My invention relates to improvements on 10 that for which application for a patent was filed December 16, 1887, Serial No. 258,065, for improvements in direct-acting steam or pneumatic engines, and wherein the piston is reciprocated in the cylinder by the action of 15 its valve without the intervention of valve-operating mechanism; and my invention has for its object to render such engines more positive and sensitive in action under high and low pressures, to obtain a steadier movement 20 of the parts, and to facilitate the handling and application of the machine when used for chipping, calking, riveting, mining, and other purposes.

It consists in the combination of a cylinder 25 bored out concentrically to two different diameters for different portions of its length, a tubular piston-rod provided with inlet and discharge passages, a distribution-valve adapted to reciprocate within said piston-rod and 30 formed with an improved arrangement of relief-passages, a rod attached to the tubular piston-rod and extending through a tubular casing projecting from the open end of the cylinder, a stock or holder secured to the 35 outer end of the extension-rod for carrying a specially-constructed chisel or other appliance, and a handle adapted to the closed end or head of the cylinder for directing the machine to its work, the whole being mounted on 40 wheels for facilitating the transport and application of the machine.

On the accompanying drawings, Figure 1 represents a central longitudinal section of 45 my improved direct-acting engine adapted for use as a chipping device in mining operations, the piston being shown at the outer termination of its stroke; Fig. 2, a detached view, to an enlarged scale, of a portion of the piston and distribution-valve seen in Fig. 1; Fig. 3, 50 a sectional plan on line 11 in Fig. 2; Fig. 4,

a similar view on line 22 in Fig. 1; and Fig. 5, a side view of the chipping-tool seen in Fig. 1, like letters of reference denoting like parts in all the figures.

a represents the cylinder, which is bored 55 out concentrically to two different diameters extending in opposite directions from a plane at or near the middle of its length and corresponding, respectively, with the diameters of its piston *b* and of a tubular piston-rod, *c*, 60 which is formed in one piece with or secured to the piston *b*. The piston *b* and tubular piston-rod *c* are bored out centrally to provide a cylindrical chamber or cavity, *d*, which extends from its open end, where it is flush with 65 the outer side of the piston *b*, to a suitable depth within the tubular piston-rod *c*, the inner end of which is extended by means of a square (or other) shaped piston-rod, *c'*, passing through the open end of the cylinder *a*, and 70 through and beyond a cylindrical tubular casing, *a'*, which is secured at its open end to the corresponding end of the cylinder *a* and closed at its outer end, so as to form a bearing and 75 guide thereat to the extension piston-rod *c'*. By this arrangement an annular space, *e*, is formed between the extension piston-rod *c'* and tubular casing *a'*, from which space *e* and from the cylinder *a* exhaust-passages *n' n''*, respectively, open into the external atmosphere. 80

In the outer open end of the chamber *d* is fitted and fixed a cylindrical tube or sleeve, *g*, which is flush at its outer end with the outer side of the piston *b* and extends a certain distance within the chamber *d*. Into the inner 85 end portion of this tube or sleeve *g* projects the outer diametrically-reduced end portion of a cylindrical distribution-valve, *h*, which to the extent of that portion of its length beyond the shoulder of its reduced end is fitted to and 90 capable of reciprocation within the chamber *d*, and is formed with a longitudinal central supply-passage, *i*, extending from its outer open end, inclosed by the tube or sleeve *g*, to a suitable depth therefrom, one or more inlet- 95 passages, *j*, being formed near the inner closed end of the supply-passage *i*, through the wall of the distribution-valve *h*, and communicating with an annular space, *k*, formed by a circumferential recess in the interior surface of the 100

tubular piston-rod *c*, surrounding the chamber *d* in conjunction with the circumferential surface of the distribution-valve *h*.

5 *l l'* are inlet-passages leading to the chamber *d*, through the wall of the latter from the outside of the tubular piston-rod *c* and communicating with each other by open grooves *l*, formed in the outer surface of the tubular piston rod *c*.

10 *m* is an inlet and outlet passage located on the outside of the tubular piston-rod *c* beyond the inlet passages *l*, and extending through the wall of the tubular piston-rod *c* and through the inner end of the chamber *d*, with 15 which it communicates behind the distribution-valve *h*; and *n* are exhaust-passages extending from the interior of the tube or sleeve *g* through the wall of and surrounding the latter and longitudinally through a portion of 20 the piston *b* and wall of the tubular piston-rod *c* to the space *c* surrounding the extension piston-rod *c'*.

In the circumferential surface of the reduced outer end of the distribution-valve *h*, where it enters the tube or sleeve *g*, are formed channels or passages *f'*, which in certain positions of the distribution-valve *h*, as hereinafter more particularly explained, establish communication from the annular space occurring between 25 the inner end of the tube or sleeve *g* and the said shoulder of the distribution-valve *h* to the exhaust-passages *n*.

To the end of the extension piston-rod *c'*, external to its guide or outer end of the tubular 30 casing *a'*, is fixed a stock or holder, *g'*, for receiving and holding the chipping tool *h'*, (or other appliance, as the case may be.) The chipping end of this chisel *h'* is splayed off to one side only and formed centrally for some 35 distance backward from its edge with a slot, *i'*, the inner end of which is V-shaped and inclined upward toward the beveled side of the tool, by which device the material operated upon is more easily disintegrated than by the 40 ordinary chisel.

45 Steam or other motive fluid is admitted to the machine through a flexible hose or other pipe attached to the nozzle *o'*, which opens directly into the cylinder *a* at the inner end of its larger diameter, the flow of steam being 50 regulated, according to the quantity required, by any suitable description of stop or regulating valve.

The handle *s'*, for holding the machine to its 55 work, is attached to the closed end or head of the cylinder *a*, and the entire apparatus mounted on wheels *k'*, the axle *p'* of which has its bearings in a boss or enlargement, *q'*, or other suitable provision therefor on the circumference of the cylinder *a*.

60 In operation, the parts being in the position seen in Fig. 1, the operator locates the machine, by means of its wheels *k'* and handle *s'*, into the desired position for the work, and the 65 motive fluid, being admitted through the nozzle *o'*, enters the cylinder *a* on the inner side of the piston *b*, as indicated by the ar-

rows, and circulating around the tubular piston-rod *c* passes through the inlet-passages *l* and around the annular space *k* into and 70 through the inlet-passages *j* and central supply - passage, *i*, of the distribution-valve *h*, through the tube or sleeve *g* to the outer side of the piston *b*, which, with the tubular piston rod *c*, is thereby forced toward the inner 75 open end of the cylinder *a*, and carrying with them the extension piston-rod *c'* and stock or holder *g'*, causes the chipping chisel *h'* to strike upon the material to be dislodged. Meanwhile the outlet-passage *m*, on reaching the exhaust-passage *n'*, through the wall of the small portion of the cylinder *a* (corresponding with the diameter of the tubular piston-rod *c*) and the inlet-passages *l l' l'*, entering the same part of the cylinder *a*, and being thereby closed to 80 the ingress of steam, the steam which was behind and held the distribution valve *h* in its outward position is exhausted through the passages *m* and *n'*, and allows the distribution-valve *h* to be forced toward the inner end of 85 the chamber *d*, so as to close the inlet-passages *l l' l'*, and thereby prevent the subsequent entrance of live steam to the central supply-passage, *i*.

To prevent the accidental outward stroke of 90 the distribution-valve *h* in the chamber *d* during the return-stroke of the piston *b*, a slight back or inward pressure is imparted to the valve *h* by small inlet-passages *x*, which are located at or near to the inner side of the piston *b*, and open from the outside of and through the wall of the tubular piston-rod *c* into the chamber *d*, between the shoulder of the valve *h* and the inner end of the tube or sleeve *g*. Simultaneously, by the inward movement of the distribution-valve *h*, its outer reduced end portion uncovers the exhaust-passages *n*, through which, and through the exhaust-passage *n'* in the casing *a'*, the steam from the outer side of the piston *b* is exhausted into the atmosphere, and the steam contained in the annular space on the inner side of the piston *b* presses upon the annular surface of the latter, and thereby forces the piston *b*, with the tubular piston-rod *c*, toward the outer closed end of the cylinder *a*, or so as to withdraw the chisel *h'* from the material until the inlet-passage *m* rises just above the upper end of the said small portion of the cylinder *a*, when the steam from the space on 100 the inner side of the piston *b* enters the passage *m* and chamber *d*, and forces the distribution-valve outward to its original position, or with the shoulder of its reduced end bearing against the inner end of the tube or sleeve *g*, thereby again opening communication between the inlet-passages *j*, *k*, and *l* for admitting the steam or air to the outer side of the piston *b* and between the passages *l* and *l'*, admitting steam behind the distribution-valve 105 *h*, for supporting the latter in the outward position while the piston *b* is performing its return-stroke. During the outward movement of the distribution-valve *h*, as described and 110

indicated by the central arrow in Fig. 2, the steam or air occupying the space between the inner end of the tube or sleeve *g* and the shoulder of the distribution-valve *h*, after the small 5 inlet-passages *x* have been closed by the valve *h*, passes off through the channels or depressions *f'* into the exhaust-passages *n*, and thereby prevents the cushioning or impediment to the free outward movement of the distribution-valve *h*.

By the use of the extended piston-rod *c'*, guided by the outer end of the tubular casing *a'*, greater steadiness and precision, combined with less friction and increased sensitiveness 15 of action, are imparted to the piston *b* and its appendages, and owing to the length of bearing the blow of the chisel *h* against the material does not jar the mechanism to the same extent as when using a hammer on the end of 20 the tubular piston-rod *c*, as described in my said application. Again, by mounting the machine on wheels it can be directed and held in position with greater ease and steadiness than if held by the hands.

25 I claim—

The combination of a cylinder, *a*, a piston, *b*, fitting therein, a tubular piston-rod, *c*, formed on or secured to said piston and provided with separate inlet and exhaust passages *l* and 30 *n*, respectively, a distribution-valve, *h*, fitting within a chamber or cavity, *d*, in said piston-

rod and having a central supply-passage, *i*, extending from its open end to lateral ports *j*, and annular passage *k*, adjacent to the inner end of the chamber *d*, the ports *j* and passages *ik* 35 being so arranged as to communicate alternately with the said inlet and exhaust passages *l*, *n*, inlet-passages *l'* in the tubular piston-rod *c*, communicating with that portion of the chamber *d* beneath the distribution-valve *h*, and communicating by connecting-passages *l'* with the inlet-passages *l*, a combined inlet and exhaust passage, *m*, in the piston-rod *c*, leading to and from the chamber *d*, behind the distribution-valve *h*, inlet passages *x* in the piston-rod *c*, 45 communicating with the chamber *d* above the upper shoulder of the distribution-valve *h* when in its extreme inner position, and relief-passages *f'*, formed in the periphery of the tube or sleeve *g*, the whole operating 50 to positively hold and reverse the distribution-valve *h* at the proper times, and so govern the supply and exhaust of motive fluid to and from the piston *b* and distribution-valve *h*, substantially as shown and described. 55

In testimony whereof I affix my signature, in presence of two witnesses, this 11th day of April, 1888.

GUSTAV A. BARTH.
